UNITED STATES PATENT OFFICE.

CHARLES H. HAESLER, OF PHILADELPHIA, PENNSYLVANIA.

CONDIMENT DISPENSER.

Application filed January 18, 1922. Serial No. 530,084.

To all whom it may concern:

Be it known that I, CHARLES H. HAESLER, a citizen of the United States, residing at Philadelphia, county of Philadelphia, State of Pennsylvania, have invented a new and useful Condiment Dispenser, of which the following is a specification.

My invention comprehends a novel condiment dispenser wherein a novel construction of a valve is employed and novel means are provided for actuating such valve.

It further comprehends a novel construction of a container and cover therefor and novel valve mechanism which includes novel means for guiding and placing the proper tension on the valve and for confining the spring to prevent any deleterious action of the condiment on the spring of the valve mechanism.

It further comprehends a novel construction of a condiment dispenser wherein the cover is removable for the purpose of refilling the dispenser and wherein provision is made for limiting the adjustment of the valve on its stem to prevent injury to the actuating mechanism.

It further comprehends other novel features of construction and advantage as will be hereinafter fully set forth.

For the purpose of illustrating my invention, I have shown in the accompanying drawings embodiments thereof which are at present preferred by me, since these embodiments will be found in practice to give satisfactory and reliable results. It is, however, to be understood that the various instrumentalities of which my invention consists can be variously arranged and organized and that my invention is not limited to the precise arrangement and organization of these instrumentalities as herein shown and described.

Figure 1 represents a section on line 1—1 of Figure 2, of a condiment holder, embodying my invention.

Figure 2 represents a section on line 2—2 of Figure 1.

Figure 3 represents a section on line 3—3 of Figure 1.

Figure 4 represents a section on line 4—4 of Figure 1.

Figure 5 represents, in side elevation, different embodiments of valve operating members.

Similar numerals of reference indicate corresponding parts.

Referring to the drawings,

1 designates the container of a condiment holder embodying my invention. The casing may be made of any desired material such as, for example, sterling silver, britannia metal, various compositions, or alloys, or in fact of any desired material which would not be affected by the action of the condiment to be dispensed.

The contour of the container varies in accordance with conditions and requirements met with in practice and the character of the condiment or comminuted material it is to dispense. The casing 1 is provided with a removable cover 2 in threaded engagement with it as at 3. The casing 1 has a condiment receiving chamber 4 the walls of which at their lower portions preferably curve or incline inwardly, as at 5, towards the discharge port 6, the wall of which is preferably substantially straight. The port 6 merges into the flaring bottom chamber 7, the wall of which converges towards the port 6 and in proximity to such port forms a bearing or seat for the inclined face 8 of a valve 9 adjustably carried by a valve rod 10. The valve 9 has an annular pocket 11 above its seat, the bottom wall of such pocket extending laterally and its side wall being curved. The top wall of the valve diverges downwardly to facilitate the feed toward the discharge port 6 of the material being dispensed.

The valve 9 has a threaded aperture 13 opening through its top but not through its bottom and the lower end of the valve rod is threaded, as at 14. The valve 9 is preferably provided with a knurled head 15 to facilitate its adjustment.

The wall of the chamber 4 near its upper end is provided with pockets 16 in which is seated a guide member 17 in the form of a bar or plate, the ends of which are preferably curved in order to closely engage the walls of the pocket 16. The guide member 17 is provided with an elongated depending bearing sleeve 18 through which the valve rod 10 passes and in which it has a working fit. The guide member 17 has 100 extending upwardly from its bar a spring confining sleeve 19 which opens at its upper end and is adapted to receive a spring 20 which preferably encircles the valve rod. The sleeve 19 has a key 21 which co-operates 110 with a key-way 22 in a sleeve 23 into which latter the sleeve 19 telescopes so that a sec-

tional casing is provided to confine the spring 20 and prevent the condiment, such as for example salt, coming into close proximity to it. The upper sleeve 23 is carried by a manually actuated pressure piece 24. The sleeve 23 is slidably mounted in an aperture 25 in the cover 2. The wall of the aperture 25 and the outer wall of the sleeve 23 are preferably substantially straight to form proper bearing surfaces. The upper end of the valve rod 10 is secured to the pressure piece 24 in any desired manner.

In order to prevent any condiment which would have a deleterious action on the spring from coming into contact with it, I provide a disc 26 which closely fits a groove 27 in the cover 2 so as to be carried by it, and this disc is apertured, as at 28, so that it will pass over the sleeve 19.

In order that the pressure piece 24 will be indicative of the character of the material to be dispensed, it may have different shapes or colors and for the purpose of illustration, I have shown one which is white, as seen at 29 in Figure 5, which would be indicative of salt; one which is red, as seen at 30, which would be indicative of red pepper or paprika; and one which is black, as at 31, which would be indicative of black pepper.

Assuming now that it is desired to fill the dispenser the cover 2 is unscrewed and the condiment placed in the container 1. The cover is then replaced and screwed into position. The valve 9 is adjusted on its stem to provide for the proper flow of condiment.

When the pressure piece 24 is pressed downwardly against the spring 20, the valve moves away from its seat permitting the condiment to discharge, and when the pressure is released the spring 20 effects the closing of the valve. Special attention is directed to the fact that the spring is effectively sealed from the condiment. The spring is contained within the telescoping sleeves 19 and 23. The disc 26 has a tight fit in the cover and a working fit with the sleeve 19. The valve stem has a working fit in the elongated bearing sleeve 18. It will thus be seen that a triple seal is provided to prevent the condiment coming into contact with the valve actuating spring. The pocket in the valve facilitates the discharge of a thin stream of the condiment through the discharge port when the valve is opened. The cover can be removed without affecting the valve mechanism and the valve can be adjusted as desired without removing the cover.

The pressure piece may be indicative of the character of the condiment being dispensed so that where several dispensers are employed, it is not necessary to open or

test them to determine which one contains the desired condiment. The sleeve 23 contacting with the bar of the guide member limits the downward movement of the valve stem so that the device is fool proof. 70

Attention is directed to the fact that in my present construction the valve stem is not freely rotatable since the pressure piece is keyed to the sleeve with which it forms a container for the spring. If the valve stem 75 were freely rotatable the friction of the valve on its seat would tend to vary its adjustment. The adjustment of the valve is not affected during the operation in my present construction, since the valve stem and 80 valve do not rotate when they are being actuated to effect the discharge of the condiment from the dispenser.

It will be apparent that I prevent the air entering the container as to have a deleterious effect on the condiment, for example, if salt is used, the moisture in the air would tend to cake the salt, and if other condiments, such as pepper were employed, the strength of the pepper would deteriorate 90 due to the action of the air.

The valve serves to prevent access of air to the main body of the condiment, and the upper end of the container is sealed by the disc 26, so that the condiment can be maintained in its proper condition and strength. 95

The pressure piece has a sliding fit in the cover, and, owing to the elongated bearing 18 the disc 26 and the telescoping construction of the portion which seals the spring, 100 there is no opportunity afforded for the condiment coming into contact with the spring.

The purpose of limiting the longitudinal adjustment of the valve on its stem is to prevent the valve being screwed in so far as 105 to prevent any movement of the valve and valve rod. This renders the device fool-proof and the device is always in condition to properly dispense the condiment which it contains. 110

It will now be apparent that I have devised a new and useful condiment dispenser which embodies the features of advantage enumerated as desirable in the statement of the invention and the above description, and while I have, in the present instance, shown and described preferred embodiments thereof which will give in practice satisfactory and reliable results, it is to be understood that these embodiments are susceptible of 115 modification in various particulars without departing from the spirit or scope of the invention or sacrificing any of its advantages.

Having thus described my invention, what I claim as new and desire to secure by Let- 125 ters Patent, is:

1. In a condiment dispenser, a container having a lower discharge port terminating in a downwardly flaring valve seat, a valve stem terminating in a pressure piece extend- 130

ing exterior of said container, a valve coacting with said seat and in threaded engagement with the lower end of said stem, and having limited longitudinal adjustment in 5 one direction thereon, a valve stem guide bar at the upper end of said container through which said valve stem passes, said bar having an upwardly extending spring confining sleeve open at its top, a pendant sleeve carried 10 by said pressure piece and telescopically arranged with respect to said spring confining sleeve, a spring within said sleeves for keeping said valve normally seated, interlocking devices common to said sleeves for 15 preventing rotation of said pressure piece, and a disc above said bar for isolating said spring from the contents of the container.

2. In a device of the character stated, a container open at its top and having a downwardly flaring valve seat at its bottom, and a cylindrical wall above said valve seat, an upwardly seating valve for said seat having 20

a threaded hole extending partially into said valve, a valve stem in threaded engagement with said seat, a cover for said container, a pressure piece slidingly mounted in the top 25 of said cover and connected to said valve stem, a pendant sleeve carried by said pressure piece, a transverse bar in the upper portion of said container and provided with an 30 upright sleeve open at its top, interlocking devices common to said sleeves for preventing rotation of said pressure piece, valve stem, and valve, a spring contained within said sleeves and pressing up on said pressure piece to seat said valve upwardly, and a disc secured between said cover and container 35 for isolating said spring from the contents of the container.

CHARLES H. HAESELER.
